REFRIGERATING APPARATUS

Alex A. McCormack, Dayton, Ohio, assignor to
General Motors Corporation, Dayton, Ohio, a
corporation of Delaware

Application November 29, 1933, Serial No. 700,160

1 Claim. (Cl. 230—24)

This invention relates to refrigerating apparatus and more particularly to motor-compressor units wherein means are provided for completely unloading the compressor during the starting operation.

It is desirable in refrigerating apparatus, when utilizing a low starting torque motor, to provide some means for completely unloading the compressor during the starting operation. Various means and instrumentalities have been suggested for performing this function. Some of these devices have unloaded the compressor at the time of starting and others during the idle period of the compressor but as far as I am aware, however, most of these devices are not simple in operation nor are they particularly economical. Particularly when such devices are to be used in a sealed motor-compressor unit it is advantageous to eliminate as many moving parts as possible. This will not only reduce the amount of trouble which would be encountered by a complicated device but would be more economical from the standpoint of construction.

My invention has for its object the provision of an improved type of unloading device, simple in construction, easy to assemble and adapted to be actuated by the gas discharged directly from the compressor.

More specifically the object of my invention contemplates the provision of an unloading device located entirely on the high pressure side of the refrigerating system and adapted to control communication between the high and low pressure sides of the compressor in response to the pressure of the discharge from the compressor.

Further objects and advantages of the present invention will be apparent from the following description, reference being had to the accompanying drawing, wherein a preferred form of the present invention is clearly shown.

In the drawing:

Fig. 1 is a sectional view of a sealed motor-compressor unit together with the diagrammatic elements of the component parts of a refrigerating system;

Fig. 2 is an enlarged fragmentary sectional view of the unloading mechanism;

Fig. 3 is a fragmentary view taken on line 3—3 of Fig. 2, and

Fig. 4 is a small top view of the compressor element taken on line 4—4 of Fig. 1.

Referring now to the drawing and more particularly to Fig. 1, as a preferred embodiment of my invention, I have shown a sealed motor-

compressor unit generally designated by 10, comprising an electric motor 11 which drives the compressor element 12. Gaseous refrigerant compressed by the compressor 12 passes to the condenser 13 where it is condensed to a liquid and stored in the receiver 14 until required for use according to the demand of the refrigerating system. Liquid refrigerant is delivered from the receiver 14 to a cooling coil 15 through a refrigerant line 16 and is admitted to the cooling coil 15 under the control of an expansion valve 17 of any suitable type. The liquid refrigerant vaporized in the cooling coil 15 by the absorption of heat therein is withdrawn therefrom through the suction line 18 by the action of the compressor 12 where it is again compressed and circulated according to the described cycle.

Means are provided for automatically controlling the operation of the motor compressor unit and in this modification this means is shown in the form of a snap acting electric switch 20 interposed in the electric circuit 21 of the motor 11. The snap acting switch 20 has a motive power element, such as a sylphon bellows 22 which is responsive to the changes in pressure in the thermostat bulb 23, so as to operate the switch to open and close the contacts thereof and thus interrupt the electric circuit 21 to the motor 11 of the motor-compressor unit. The thermostat bulb 23 is responsive to the temperature changes of the cooling coil 15 and thus responsive to the refrigeration demand thereof.

Referring more particularly to the motor-compressor unit, there is provided a cylindrical metal casing 30 in which the component parts of the motor-compressor unit are located. The casing 30 is provided with a top horizontal wall 31 which supports the compressor element 12 and substantially closes that end of the casing. The bottom end of the casing 30 is sealed by means of a removable wall 32 secured and sealed in place by a gasket 33 and a suitable clamping ring 34. Bolts 35 extend through the clamping ring 34 and are threaded into bosses 36 provided on the casing 30 so as to retain the ring 34 and gasket 33 in place. An electric motor 11 is located in the space provided between the walls 31 and 32 of the casing 30 and is supported by means of bearings 37 and 38, said bearings being integral parts of the walls 31 and 32 respectively.

The motor shaft 39, of the electric motor 11, is positioned vertically within the casing 30 and the lower end thereof rests upon a substantially frictionless bearing 40 consisting of a hardened steel button semi-circular in shape. The upper

end of the motor shaft is provided with an extension 41 which is eccentric to the motor shaft 39 and is adapted to operate the compressor element 12 upon rotation of the shaft 39. The compressor element 12 is enclosed within a chamber provided by a cap member 43 which is secured and sealed to the casing wall 31 by means of a gasket 44 and bolts 45. Bolts 45 extend through a flange 46 provided on the cap 43 and threaded into suitable threaded holes 47 in the casing 30.

The compressor element 12 consists of a circular shaped disc member 50 having a concentric flange 51 as an integral part thereof. The flange 51 operates in a groove 52 provided in the casing wall 31. The surface faces of the flange 51 and the bottom face of the disc member 50 are adapted to provide a moving seal on the surfaces of the groove 52 and the face 53 of the wall 31. The cooperation of the groove 52 and the disc member 50 provides a space 55 wherein gaseous refrigerant may be compressed. The eccentric extension 41, of the motor shaft 39, protrudes through the center of the disc member 50 and is adapted to impart a gyratory motion thereto. A ball bearing, bearing member 57 is provided between the eccentric 41 and the disc 50. The gyratory action of the compressor withdraws gaseous refrigerant from the evaporator 15 through the suction line 18, compresses same in the chamber 55 and discharges the compressed gas through the discharge valves 56 into the chamber 42. The suction inlet side 78 of the compressor is separated from the discharge side 35 by a divider block 58.

As previously stated, the wall 31 of the casing 30 substantially closes that end of the casing. The only openings through the wall 31 are the bearing opening, through which the motor shaft 40 39 extends, thereby substantially closing same, and the openings for the unloading device, to be more fully explained. It will thus be seen from the drawing that the chamber 42 into which the compressed gases are discharged is isolated, and 45 from which no gas can escape to the condenser of the refrigerating system, except by way of the passage 65, passage 64 and chamber 66.

In operation gaseous refrigerant is withdrawn from the evaporator through the conduit 18, chamber 79, and passage 78 whereby it enters the compressor 12 of the motor-compressor unit. The refrigerant gas is compressed by the compressor and discharged into the chamber 42, from which it may pass to the condenser 13 through 55 passages 65, 64 and chamber 66.

Means are provided to unload the compressor when the same comes to a stop after a cycle of operation. To accomplish this function I provide a piston in the passage 64 which piston actuates 60 a valve for controlling communication between the high pressure chamber 66 and the suction passage 78 of the compressor.

For example, my device more specifically is located in a recess 60 provided in the casing 30 65 of the motor-compressor unit.

This device consists of a piston 61 which has a hollow central portion 62. The side wall of the piston is provided with slots 63 so that gases may pass from the hollow portion of the piston 70 through the side walls. This piston cooperates, in a sliding fit relation, with a vertically located hole 64 provided in the side wall of the casing 30. The hole 64 communicates with the chamber 42 by means of a drilled hole 65 and with the motor 75 chamber 66 through the slots 63 of the piston 61.

The chamber 42 thereby has an outlet through which the compressed gases may escape. The compressed refrigerant gases leave the motor chamber 66 through an opening 67 provided in the wall of the casing 30, thereby passing to the condenser 13 of the refrigerating system. The piston 61 moves vertically within the hole 64 and rests against a shoulder 65, provided in the hole 64, when in its upward limit of travel. A coiled spring 66 is located under the piston and is confined between the bottom of the piston 61 and the bottom wall of the recess 60. The compression of the spring 66 thereby tends to maintain the piston 61 against the shoulder 65. When the piston is in this position, at which time the motor-compressor unit is idle, the slots 63 are above the top wall of the recess 60 so that gas cannot pass from chamber 42 to chamber 66. A boss 67 is secured to the top wall of the recess 60 and has a lever 68 pivoted thereto at 69. The lever 68 is provided with yokes 70 and 71 on opposite ends thereof. The yoke 70 is adapted to fit around the piston 61 and is pivotally secured thereto by a pin 72. The opposite end of the lever carrying the yoke 71 fits around a solid member 73 and is rigidly secured thereto. The solid member 73 is provided with a hole therein in which a needle valve 75 is slidably mounted and is retained in an upward position by a coiled spring 76. The valve is spring mounted in this manner so that 30 the piston of the unloading device may vary in its position during the running time of the compressor to a certain extent without causing the valve to lift off its seat in the passage 77. This needle valve is adapted to close a passage 77 35 which connects the chamber 66 with the suction inlet 78 of the compressor 12 so that gases from the high pressure side of the system may enter the suction side of compressor when the unloader operates to open the passage 77 and unload same. 40

Between the suction inlet 78 of the compressor and the suction line 18 of the refrigerating system a check valve 80 is provided within a capacity chamber 79. This check valve consists of a disc type valve 81 adapted to rest upon a 45 seat 82 when there are no refrigerant gases passing therethrough and when the pressure in the suction side of the compressor is above that in the evaporator due to the action of the unloading device.

When the motor-compressor unit is idle the unloading device will assume a position as shown in the drawing wherein the piston 61 will be pushed upwardly against the shoulder 65 of the hole 64 by the spring 66 wherein the slot 63 will be above the top face of the recess 60. In this position the chamber 42 will have no communication with the chamber 66 with the exception of a bleeder hole 85 which will be hereinafter explained. The needle valve 75 will be withdrawn from its seat in the end of the passage 77 whereby the chamber 66 will be in open communication with the suction inlet 78 of compressor, thereby permitting high pressure gas from the chamber 66 to enter the suction side of the compressor so that the pressure in the suction side of the compressor will be the same as that existing in the chamber 66 and chamber 42 at the time of starting. Since both sides of the compressor are at the same pressure, the motor may 70 start under an unloaded condition and a low torque motor may be used.

When the motor starts, in response to the closing of the electric switch 20, high pressure gaseous refrigerant from the chamber 66 will enter 75

the chamber 55 of the compressor and be discharged through the valves 56 into the chamber 42. It is to be remembered that chamber 42 has no outlet except through openings 65 and 64 and the piston 61, hence a higher pressure will be built up therein than is present in chamber 66 and the condenser 13 of the refrigerating system. This increase in pressure in chamber 42 and its communicating openings exerts its force 5 on the piston 61 and will move the piston downwardly against the action of the retaining spring 66 to a position where the slots 63 will be open to the recess 60 and hence to the motor chamber 66. While the piston is moving downwardly, 10 the lever 68 is carrying the needle valve 75 upwardly to close off the passage 77. When the needle valve has thus closed off the passage 77, high pressure refrigerant gas can no longer enter the suction passage 78 of the compressor 12, 15 20 at which time the compressor may then withdraw gaseous refrigerant from the evaporator after it has reduced the pressure in the suction passage 78.

The pressure in the chamber 42 will be maintained above that in the motor chamber 66 as long as the motor-compressor unit is operating due to the fact that the compressed gases cannot pass to the condenser 13 of the refrigerating system without passing through the restriction 25 caused by the piston 61 and slot 63. The degree of restriction to create the pressure differential between the chambers 42 and 66 is determined by the tension of the spring 66, thereby any operating differential may be obtained by changing the spring 66 or the amount of compression 30 thereof. This pressure differential will be maintained between the chambers 42 and 66 as long as the compressor is in operation due to the fact that a definite primary increase in pressure is 35 needed to move the piston 61 and when this point is reached a balanced condition will result between the pressure exerted downwardly on the piston by the pressure of the gas and the pressure exerted upwardly thereon by the spring 66 40 so that the quantity of gas permitted to pass through the piston will equal the output from the compressor. As long as this differential in pressure is maintained between the two chambers, the needle valve 75 will be held in a seated po- 45

sition in the opening 77, thereby preventing high pressure gaseous refrigerant from entering the suction side of the compressor at any time during the operation of the compressor.

When the control switch 20 breaks the electric circuit to the motor of the motor-compressor unit in response to the cooling coil 15, the compressor will gradually come to a stop. At this time the pressures in chambers 42 and 66 are equalized by the escape of gases from the chamber 42 to the chamber 66 through the slots 63 and the bleeder hole 85 in the side wall of the piston 61. The bleeder hole 85 is provided so that an exact equalization of pressure may be accomplished between the chambers 42 and 66 10 whereby the piston 61 will move to its full upward position to fully open the unloading passage 77. The compressor unit is now in position to make another start in an unloaded condition. 15 20

While the form of embodiment of the invention as herein disclosed constitutes a preferred form, it is to be understood that other forms might be adopted, all coming within the scope of the claim which follows. 25

What is claimed is as follows:

A motor-compressor unit comprising a casing, a sealing dividing wall extending across the casing to divide the casing into two compartments, a compressor located in one of said compartments, an electric motor in another of the compartments for driving the compressor, said compressor having a discharge outlet discharging into its compartment, the dividing wall structure of said casing being provided with a restricted passage connecting said compartments through which fluid discharged by said compressor flows, said compartment containing the electric motor being provided with an outlet for compressed fluid, and an unloading device for 30 said compressor including means for restricting the flow of fluid through said passage whereby a pressure differential is set up between said compartments, said unloading device being actuated by the pressure differential between said 35 compartments to unload the compressor during its starting period and to load the compressor 40 during normal operation. 45
